[57] ABSTRACT

Nitrodifluoraminoterphenyl compounds having the
structural formula:

wherein R may be H or NO₂. When R = H the compound is 3,3''-Bis(difluoramino)-2,2'',4,4',4'',6,6',6''-octanitro-m-terphenyl (DDONT) and when R = NO₂ the compound is 3,3''-Bis(difluoramino)-2,2',2'',4,4',4'',6,6',6''-nonanitro-m-terphenyl (DDNONA). Procedures are described wherein diamino precursors of the indicated compounds are prepared and the final compounds are obtained by a fluorination operation. The compounds are highly energetic and suitable for use as explosives and particularly in exploding bridge wire (EBW) detonators.

3 Claims, No Drawings

NITRODIFLUORAMINOTERPHENYL
COMPOUNDS AND PROCESSES

BACKGROUND OF THE INVENTION

The invention disclosed herein was made under or in the course of Purchase Order No. 58-5131 under Contract No. AT(29-1)-789 with the United States Atomic Energy Commission.

A number of highly energetic explosives derive their energy from nitro, e.g., 2,4,6-trinitrophenyl groups. These explosives are highly stable to impact, shock, friction, electrostatic charges, high temperatures and the like. However, most are insensitive to initiation except by strong explosive shocks produced by sensitive detonators or composite detonator assemblies and are not generally susceptible to initiation by EBW (exploding bridge wire) detonation systems. Explosive compositions including the highly energetic trinitrophenyl (nitroaromatic) moiety with its inherent advantages but which could also be sensitized to EBW initiation would be valuable additions to the available stack of explosive compositions.

In classical electrical high explosive detonator systems there is employed a fuse wire adjacent to which there is disposed a primary explosive such as mercury fulminate, lead azide, lead styphnate, or other deflating explosive material, in an amount sufficient to detonate a base charge of high explosive such as pentaerythritol tetranitrate (PETN), trimethylene trinitramine (RDX), tetryl or the like disposed adjacent thereto. The electrical current heats the fuse wire to the melting point igniting the sensitive primary material which then detonates the base charge producing a detonation or shock wave of sufficient magnitude to detonate a large quantity of more stable high explosive to subsequently produce most of the energy obtained in the detonation.

The primary materials employed in such classical detonators are very sensitive to mechanical shock and also to induced electrical or accumulated static charges so that extreme precautions are required to avoid inadvertent initiation. While satisfactory for usual blasting purposes, if appropriate precautions are observed, it will be noted that a relatively long and somewhat variable time period, i.e., a millisecond or greater, with a similar time period spread, elapses on application of the electrical current until the detonator ignites. It is not possible using such detonators to obtain a precise detonation time or precise sequencing or simultaneity of detonation in multiple detonation point arrays where time factors of the order of microseconds or less is of critical importance.

One approach developed in the prior art for obviating

the difficulties associated with the use of the classical electric detonator involves the use of an exploding bridge wire to detonate a base or booster charge directly. For example, U.S. Pat. No. 3,040,660, issued Jun. 26, 1962, to Lawrence H. Johnston, discloses such a device in which a bridge wire of a few thousandths of an inch diameter and a fraction of an inch in length is arranged in proximity to a quantity of an explosive of the detonating type (PETN) ordinarily used as a base or booster as described above. Another system employing an exploding bridge wire is disclosed in U.S. Pat. No. 3,158,098 issued Aug. 9, 1963, to Robert S. Reith et al. Such secondary base or booster explosives are substantially insensitive to spark or shock initiation but are sufficiently sensitive to be detonated by a shock produced by an exploding bridge wire with reasonable amounts of electrical energy delivered therethrough as a short time duration fast rising pulse therethrough. This arrangement greatly improves the precision and reproducibility of the time at which an initiating detonation can be made to occur. In usual practice such an arrangement may be employed for detonating the much more insensitive and highly energetic explosives such as TNT (trinitrotoluene) and other nitrated aromatic carbon compounds which can be detonated reliably only by means of a very strong shock.

A procedure for preparing certain monophenyl-fluoramine-nitro compounds by the liquid phase fluorination of simple nitro-substituted nitro-phenyl compounds is disclosed in Jour. Org. Chem. 38, 1387 (1968) by C. L. Coon, M. E. Hill and D. L. Ross. In such procedure an appropriate nitro-aromatic amine dissolved in HF or acetonitrile as a solvent are fluorinated by bubbling fluorine through the solution. Such procedure is also disclosed in U.S. Pat. application Ser. No. 748,569 filed July 29, 1968 by Marion E. Hill et al., now U.S. Pat. No. 3,751,473 issued Aug. 7, 1973.

SUMMARY OF THE INVENTION

The invention relates generally to processes for producing nitrated polyaromatic hydrocarbons having difluoramino substituents and, more particularly, to processes for producing terphenyl compounds having a high proportion of nitro groups thereon together with substituents difluoramino groups in a proportion appropriate for sensitization to EBW initiation and to the novel products obtained thereby. 3,3''-BIS(DIFLUORAMINO)-2,2'',4,4',4'',6,6',6''-OCTANITRO-M-TERPHENYL (DDONT)

The first compound (I) of the invention is prepared by the following sequence of reactions:

SEQUENCE (A)

- Continued

wherein X = NO₂ 3,3''-BIS(DIFLUORAMINO)-2,2',2'',4,4',4'',6,6',6''-NONANITRO-M-TERPHENYL (DDNONA)

The second compound (II) of the invention was prepared by the following sequence of reactions:

bromo-2,4,6-trinitroanisole (VI) is obtainable by nitration of 3-bromoanisole (V) with 90percent HNO₃ in 30percent oleum (H₂SO₄ = SO₃).

Dibromodinitro benzene (IV) is then reacted with bromotrinitroanisole (V) in the presence of copper

SEQUENCE B

wherein X = NO₂

Accordingly, it is an object of the invention to provide novel nitrofluoramino-poly-aromatic compounds for use as detonators, explosives, propellants and the like.

Another object of the invention is to provide nitroterphenyl compounds sensitized by incorporation of nitrodifluoramino groups therein which are especially useful in EBW initiator systems.

Still another object of the invention is to provide processes for producing nitrodifluoraminoterphenyl compounds.

Other objects and advantageous features of the invention will be apparent in the following description of the invention.

DESCRIPTION OF PREFERRED EMBODIMENTS

3,3''-BIS(DIFLUORAMINO)-2,2',4,4',4'',6,6',6''-OCTANITRO-M-TERPHENYL (DDONT)

The first compound of the invention is prepared by reactions 2-6 shown above and described generally as follows: 4,6-dinitro-1,3-dibromobenzene (IV) is obtainable by reaction (1) as by nitration of dibromobenzene (III) using a mixture of KNO₃ in H₂SO₄ (96percent) (Beilstein 5, 268). As shown in reaction (3) 3-

50 metal (Cu⁰) to yield dimethoxyoctanitroterphenyl (VII) as indicated in reaction (4). Reaction 4 may be erratic with regard to reproducible product yields. However, it is found that activation of the copper assures consistently high yields of (VII). Such activation involves the treatment of the copper with an iodine-acetone solution followed by washing with dilute hydrochloric acid an anhydrous acetone. This pretreatment of the copper undoubtedly produces trace quantities of copper iodide that are dissolved and removed by the hydrochloric acid leaving very active sites on the metal. The acetone serves to remove any traces of milling oil and moisture on the copper.

55 Dimethoxy-octanitroterphenyl is then aminated, as in reaction (5) by bubbling NH₃ through a 10percent solution thereof in 1:1 tetrahydrofuran: methanol solvent for about 0.5 hour. The crude product may be purified by dissolution in dimethylformamide and adding methanol to recrystallize the product, i.e., diamino-octanitroterphenyl (VIII).

60 Diamino-octanitroterphenyl (VIII) is then fluorinated, as in reaction 6 to yield 3,3''-Bis(difluoramino)-2,2',4,4',4'',6,6',6''-octanitro-m-terphenyl (DDONT, I). More particularly, superior fluorinating conditions comprise bubbling fluorine gas through an acetonitrile

solution of VIII at about -35°C or at least below about -25°C . It is necessary to bubble fluorine through the mixture until the starting material dissolves and until the color of the solution changes from dark orange to light orange. Further fluorination does not appear to affect the yield. Fluorination at 0° or -15°C or using anhydrous HF solvent gives much lower yields of product. Some impurities result due to incomplete fluorination and direct fluorination of the ring. Purification is accomplished as described for compound (II) and in the Examples. 3,3''-Bis(DIFLUORAMINO)-2,2'',4,4'',6,6'',6''-NONANITRO-M-TERPHENYL (DDNONA)

1,3-dibromo-2,4,6-trinitrobenzene (IX) is easily obtained by nitration of readily available m-dibromobenzene using a mixture of potassium nitrate and oleum. Such compound may be coupled with bromoanisole (V) in the presence of activated copper, reaction (7), to produce 3,3''-dimethoxy-2',4',6'-trinitro-m-terphenyl (X). A preferred procedure for the preparation of dimethoxynonanitroterphenyl (XI), Reaction 9, is the treatment of (X) with potassium nitrate in 30 percent -oleum overnight at ambient temperature and heating at 110°C for 4 to 5 hours. (XI) in yields of 15-20 percent are routinely obtained. However, (XI) was also obtained in a 15 percent yield by treatment of 3,3''-dimethoxy-2',4',6'-trinitro-m-terphenyl (X) with 90 percent nitric acid and 30 percent oleum at 130°C for 3 hours.

Because the preparation of the (XI) proceeds in low yield, a number of other methods of preparation were investigated. One synthesis attempted was the mononitration of VII to XI. Thus, VII was treated with 90 percent nitric acid and 30 percent oleum for 4 hours at 130°C ; only 20 percent of the unreacted starting material was recovered. (VIII) was also treated with KNO_3/SO_3 mixture at 130°C for 4 hours; again, only starting material was recovered. Finally, (VII) was treated with nitronium tetrafluoroborate in tetramethylene sulfone for 1 hour at 95°C , and 50 percent of the starting material was recovered. Therefore, we concluded that the central benzene ring was deactivated by the nitro groups, and the 2'-position was sterically hindered by the flanking phenyl groups, which made the nitration of VII to XI very difficult.

Two additional factors affect the synthesis of XI by nitration procedures. First, as the nitration proceeds, the polynitroterphenyl product becomes more insoluble in the nitrating medium. This is especially true with potassium nitrate-oleum mixtures. In addition, foaming is a severe problem at the higher temperatures ($110^{\circ}\text{--}130^{\circ}\text{C}$). Second, the nitrating reagents used were also strong oxidizing agents. Since the methoxy groups oxidize readily to hydroxyl, their desired functionality are easily destroyed. 3,3''-diamino-2,2'',4,4'',6,6'',6''-nonanitroterphenyl (XII) is prepared by dissolving XI in a tetrahydrofuran/methanol/dimethylformamide (50:20:2 retrorespectively) solution and bubbling anhydrous ammonia therethrough at ambient temperature as shown in reaction 10. Compound (XII) is then fluorinated preferably by suspension in acetonitrile, flushed with nitrogen, and cooled to about -35°C . A mixture of 25 percent fluorine with nitrogen is bubbled through the suspension for about 6 hours, the solution is flushed with nitrogen and diluted with methylene chloride and stirred overnight with M_2SO_4 to eliminate HF. The mixture is then evaporated

to yield a crude product gum from which the product can be extracted with ethyl acetate, which is evaporated and the residue purified on a silica gel column by elution with ethyl acetate.

5 Further details of the processes and products of the invention will be set forth in the following illustrative examples:

EXAMPLE I

10 Relevant to reaction sequence (A)

1,3-Dibromo-2,4,6-trinitrobenzene, IV [reaction (a)]

Dry potassium nitrate, 92.2 grams (0.83 mole) was added portionwise during 20 minutes to 442.4 grams of 15 30 percent oleum (1.66 mole of SO_3). A resulting exotherm raised the temperature of the mixture to 120°C . With rapid stirring of this nitration mixture, 21.8 grams (0.092 mole) of m-dibromobenzene was added dropwise during 15 minutes at 120°C . A mild exotherm was 20 observed during the addition; however, it was necessary to warm the reaction mixture with an oil bath to maintain a $120^{\circ}\text{--}130^{\circ}\text{C}$ temperature range. After the addition was complete, the mixture was stirred for 4 25 hours at 125°C , was cooled to 10°C , and was slowly quenched on 700 grams of crushed ice. The resulting aqueous mixture was extracted with four 300-ml portions of methylene chloride, the extracts were combined, and then washed with two 500-ml portions of brine. The organic phase was filtered through anhydrous sodium sulfate and evaporated to give 32.3 grams 30 (95 percent) of crude product as a yellow powder. Recrystallization of the yellow powder from 90 ml of chloroform gave 23.4 grams of Compound IV (69 percent) as yellow prisms, m.p. $136^{\circ}\text{--}137^{\circ}\text{C}$, lit. (2) m.p. 135°C .

35 3,3''-Dimethoxy-2,2'',4,4'',6,6'',6''-octanitro-m-terphenyl, VII [reaction (4)]

Activated copper powder (21.5 grams, 0.34 gram-atoms, Venus 44-F) in 50 ml of nitrobenzene was 40 heated to 125°C . A solution of 1,3-dibromo-4,6-dinitrobenzene (15.9 grams, 0.049 mole), 3-bromo-2,4,6-trinitroanisole (39.3 grams, 0.012 mole) and warm nitrobenzene (100 ml) was added in three portions. After the first 25-ml addition, no temperature 45 rise was observed, and the slurry was warmed to 135°C . With the second 25-ml addition, an exothermic reaction occurred and the temperature rose to 144°C . The metallic copper slowly took on a grey-brown color as copper bromide was formed. The remaining solution was added over 20 minutes at $135^{\circ}\text{--}140^{\circ}\text{C}$ and the slurry was stirred an additional 30 minutes at 135°C . The mixture was cooled to 60°C and filtered into a 1-liter, 3-necked flask. The nitrobenzene was removed by 50 steam distillation: this operation required approximately 5 hours. The yellow distillate was discarded, and the aqueous phase was decanted from the crude residual product, a dark gum. The gum was washed well with water, dissolved in 500 ml of boiling acetone, and treated with activated charcoal (Norit). The charcoal was removed, washed well with acetone, and the combined filtrates concentrated to about 250 ml using reduced pressure. Hot methanol (500 ml) was added, and the solution was allowed to cool. A combined total of 55 16.8 grams (53 percent yield) crystalline VII was obtained from the first crystallization and from the mother liquors, m.p. $267^{\circ}\text{--}270^{\circ}\text{C}$, reported (13) m.p. 265°C .

3,3''-Diamino-2,2'',4,4',4'',6,6',6''-octanitro-m-
terphenyl, VIII [reaction 5]

Compound VII (11.0 grams, 0.017 mole) was dissolved in 110 ml of 1/1 tetrahydrofuran/methanol and treated with a slow stream of anhydrous ammonia for 0.5 hour with no external cooling. The yellow solution turned a red-orange color within one minute and an increase in temperature was observed (~20°C). Methanol (100 ml) was added and the solution was carefully heated to boiling to remove excess ammonia. After cooling, 8.4 grams (80 percent crude yield) of VIII as a yellow product was obtained which was recrystallized by dissolving in 37 ml of hot dimethylformamide and adding methanol (15 ml). The yellow powder, VIII, 6.3 grams (60 percent) exploded at 352°C, reported (5) m.p. 355°C (exp.).

3,3''-Bis(difluoramino)-2,2'',4,4',4'',6,6',6''-
octanitro-m-terphenyl, I (DDONT) [reaction (6)]

Impure I (1.1 grams, m.p. 202°-204°C dec.) was chromatographed again on a silica gel column (15 grams, 1.1 cm. i.d.) loaded and eluted with 10 percent pentane/ benzene. Fractions of 5, 50, and 150 ml were collected. Fraction 3 gave a good TMPDA spot test and on evaporation produced a yellow solid which was recrystallized from ethyl acetate/chloroform, 0.030 grams (2 percent yield); m.p. 239°C (dec.); IR (nujol and fluorolube) 3010 (w, aromatic CH), 1580 (m, aromatic CH), 1540 (s, CNO₂), and 1340 cm.⁻¹ (s, CNO₂); NMR 89.41 (complex m, 3,5,5',5''-protons), 8.28 (s, 1,2'-proton), ϕ 62.3 (d, J_{FF} = 20.3 Hz, 3,3''-NF₂); α 25 1.75.

A. Properties of 3,3''-Bis(difluoramino)-2,2'',4,4',4'',6,6',6''-octanitro-m-terphenyl (DDONT)

Structure:

To a 360-ml Kel-F reactor was added VIII (5.0 grams, 0.087 mole) and anhydrous Nanograde acetonitrile (250ml). The resulting yellow suspension was cooled to -35°C, using a Dry Ice/ethylene dichloride bath and was flushed with nitrogen (100 ml/min for 15 min). Gaseous fluorine diluted with nitrogen was bubbled through the stirred mixture for 5 hours (20 percent F₂ in N₂ at 120 ml/min). The exit gases were vented through concentrated KI/water solution to destroy the excess fluorine. The suspension changed from yellow to red-orange to clear orange to yellow during the reaction. After 5 hours, the fluorine was discontinued and toxic gases (F₂, HF, and fluorinated CH₃CN) were flushed from the Kel-F vessel with nitrogen (120 ml/min for 15 min).

The yellow solution was filtered to remove unreacted VIII and methylene chloride (250 ml) and anhydrous magnesium sulfate (50 grams) were added to the filtrate. After stirring for 1 hour the solution was filtered and evaporated carefully using a water bath to dryness under reduced pressure. The crude yellow I was dissolved in hot ethyl acetate (~20 ml), filtered, and concentrated to an oil (6-8 ml). The oil was chromatographed on a silica gel column (125 grams, 2.6 cm) loaded with a 50 percent benzene/hexane solution and eluted with 10 percent ethyl acetate/benzene. Fractions of 125, 125, 125, 250, 25, 125, and 50 ml were collected; I moved down the column as a red band and was collected as Fraction 6, which gave a good spot test for NF₂ with TMPDA reagent (purple → yellow with heating). Upon evaporation, Fraction 6 gave 3.0 grams of yellow Crude I that exploded at m.p. 202°-204°C (dec.). TLC analysis (silica gel, 5 percent ethyl acetate/benzene, developed with UV and TMPDA indicated three components, R_f 0.14 (streak), R_f 0.32, and R_f 0.46. Preparative TLC using silica gel produced impure I (1.1 grams); R_f 0.46; m.p. 204°C (dec.).

EXAMPLE II

Relevant to reaction sequence (B)

3,3''-Dimethoxy-2',4',6'trinitro-m-terphenyl, X [Reaction (7)]

A modified Ullman procedure was used. m-Bromoanisole (187 grams, 1 mole) and 1,3-dibromo-2,4,6-trinitrobenzene (24 grams, 0.065 mole) were combined and slowly heated to 80°C. A yellow solution resulted. Activated copper (25 grams; 0.40 gram-atom) was added in 5-gram portions over a 25-minute period, while raising the temperature slowly from 80° to 130°C. Within 15 minutes, an exotherm of 8°C and production of copper bromide were observed. The gray slurry was heated at 125°-130°C for 2.5 hours, cooled, and filtered to remove the unreacted copper and copper bromides. The precipitate was washed with 150 ml of acetone and 25 ml of benzene. The filtrates and

washings were combined; the acetone and benzene were evaporated under reduced pressure. Unreacted m-bromoanisole amounting to 154 grams was distilled from the crude product at 45°-50°C (0.5 mm.). Crude black residue, 30 grams (100 percent yield), was dissolved in 500 ml of hot, anhydrous acetone and treated twice with decolorizing carbon (10 grams). The resulting clear brown solution was concentrated to about 200 ml and 300 ml of hot methanol was added. On cooling, an off-white powder was recovered, 15.3 grams (55 percent yield) with a melting point of 172°-175°C. Reported melting point is 178°C, (dec.); IR (fluorolube and nujol) 3030 (w, aromatic CH), 2950 (CH₃O), 1550 (m, CNO₂) and 1350 cm.⁻¹ (w, CNO₂).

Anal. Calcd. for C₁₈H₁₅N₃O₆: C, 56.48; H, 3.55; N, 9.88. Found: C, 56.55; H, 3.63; N, 9.73.

3,3''-Dimethoxy-2,2',2'',4,4',4'',6,6',6''-nonanitro-m-terphenyl, XI [Reaction (a)]

The nitration mixture was prepared in a 2-liter, 3-necked flask by adding 151 grams (1.5 mole) of dry potassium nitrate incrementally over 30 minutes to 800 grams of 30 percent oleum (3.0 mole of SO₃). The resulting exothermic reaction raised the temperature to 70°C. Potassium sulfate precipitated as the mixture was cooled to ambient temperature. After X (12.75 grams, 0.30 mole) was added quickly producing a temperature rise of 8°C, the slurry was cooled and stirred for 16 hours at 27°C. The slurry was then heated at 110°-113°C for 4 hours (at this temperature foaming became severe), cooled to about 40°C, and slowly quenched in 1,500 grams ice. The resulting brown aqueous solution was extracted with ethyl acetate (5 × 200 ml) and the extracts were combined, washed with water (2 × 100 ml), and dried over anhydrous magnesium sulfate. The solvent was evaporated to give 5.2 grams (25 percent) as an off-white powder. Recrystallization of the crude solid from 1/4 acetone/methanol gave 4.0 grams of XI as yellow needles; m.p. 310°C, (dec.); IR (fluorolube and nujol) 3100 (w, aromatic CH); 1540 (m, CNO₂), 1340 cm.⁻¹ (m, CNO₂); NMR (dimethylsulfoxide-d₆); 83.94 (s, 6, CH₃O), 8.90 (s, 2, 5,5''-protons), 9.22 (s, 1,5'-protons).

Anal. Calcd. for C₂₀H₁₅N₃O₆: C, 34.6; H, 1.29; N, 18.1. Found: C, 34.5; H, 1.30; N, 17.88.

3,3''-Diamino-2,2',2'',4,4',4'',6,6',6''-nonanitro-m-terphenyl, XII [Reaction (10)]

Compound XI (1.25 grams, 1.8 mole) was dissolved in 72 ml of a tetrahydrofuran/methanol/dimethylformamide (50/20/2-v/v/v). The solution was saturated with anhydrous ammonia and stirred for 30 minutes. The solution turned from a yellow to a blood-red within a few minutes and a temperature rise of 10°C was observed. The solvents were removed with reduced pressure. Methanol (50 ml) was added and the slurry was cooled and filtered. The wet, crude product, 1.3 grams, was recrystallized by dissolving in 5 ml of hot dimethylformamide and adding 50 ml of hot methanol. On cooling, the yellow powder, XII, that was recovered by filtration exploded at 355°C, 0.80 grams (66 percent

yield); IR (fluorolube and nujol) 3400 (2,NH₂), 3100 (w, aromatic CH), 1360 cm.⁻¹ (m, CNO₂); MR (dimethylsulfoxide-d₆), 88.74 (broad s, NH₂), 9.12 (s, 2, 5,5''-protons); 0.42 (s, 1,5'-protons).

Anal. Calcd. for C₁₈H₁₅N₃O₆: C, 32.50; H, 1.06; N, 23.16. Found: C, 33.98; H, 2.24; N, 22.27.

10

The NMR spectrum also indicated the presence of a small amount of dimethylformamide. This solvent which could not be removed by repeated drying with heat and vacuum, caused the inaccurate elemental analysis.

3,3''-Bis(difluoramino)--
-2,2',2'',4,4',4'',6,6',6''-nonanitro-m-
terphenyl, II/ (DDNONA) [Reaction (11)]

20 To a 325-ml Kel-F reactor was added XII (1.5 grams, 0.033 mole) and anhydrous Nanograde acetonitrile (300 ml). The resulting yellow suspension was cooled to -35°C using a Dry Ice/ethylene dichloride bath and was flushed with nitrogen (100 ml/min for 15 min).

25 Gaseous fluorine diluted with nitrogen was bubbled through the stirred mixture for 4 hours (20 percent F₂ in N₂ at 120 ml/min). The exit gases were vented through a 2-foot column of charcoal briquettes to destroy the excess fluorine. The suspension changed from yellow to red-orange to clear orange to yellow during the reaction. After 4 hours, the fluorine was discontinued and toxic gases (F₂, HF, and fluorinated CH₃CN) were flushed from the vessel with nitrogen (120 ml/min for 15 min).

30 The yellow solution was filtered to remove unreacted XII and methylene chloride (200 ml), anhydrous magnesium sulfate (10 grams), and silica gel (10 grams) were added to the filtrate. After stirring for 1 hour, the solution was filtered and evaporated to dryness under reduced pressure. Crude brown II was dissolved in hot ethyl acetate (~20 ml), filtered, and concentrated to an oil (1-2 ml). The oil was chromatographed on a silica gel column (11 mm. i.d. x 30 cc.) loaded with a 50 percent benzene/petroleum ether solution and eluted with 10 percent ethyl acetate/benzene. Fractions of 50, 40, 90, 80, 100, and 150 ml were collected; II moved down the column as a red band and was collected as Fraction 2, which gave a good spot test for NF with TMPDA reagent (purple → yellow, with heating). On evaporation, Fraction 2 gave 1.0 grams of a brown gum that darkened at 250°C, but did not melt. TLC analysis (silica gel, 5 percent ethyl acetate/benzene, developed with UV and IMPDA indicated one major component at R_f 0.53.

45 Impure II was recrystallized from ethyl acetate/benzene, giving 0.06 grams of a yellow solid, m.p. 240°C (dec.). After Fraction 3 was chromatographed again additional II, 0.04 grams was obtained, m.p. 235°C (dec.): IR (fluorolube and nujol) 3200 (w, aromatic CH), 1600 (m, aromatic CH), 1540 (s, CNO₂), and 1340 cm.⁻¹ (s, CNO₂); NMR (acetone-d₆) 89.60 (s, 1, 5'-protons), 9.55 (s, 2, 5',5''-protons) δ62.2 (s, 3,3''-NF₂).

60 Anal. Calcd. for C₁₈H₁₅N₃O₆F₄: C, 29.32; H, 0.41; N, 20.90; F, 10.31. Found: C, 30.49; H, 0.48; N, 19.45; F, 10.48.

11

Properties of DDNONA

Density

The density of DDNONA was determined with a Fischer-Davidson gravimeter by the flotation method.

Run	Density
1	1.815
2	1.812
3	1.805 Av. 1.811

EBW Sensitivity

DDNONA, mp 233°–235°C, was dried for 20 hr at 77°C (0.02 mm) and ground to 0.01 to 0.03-mm particle size. Headers were loaded with 71 to 86 mg of DDDONA, which was equivalent to 45 to 55 percent of the crystal density in the packed header. PETN, density 1.77, was ground to 0.01 to 0.03-mm particle size and loaded at 45 to 55 percent of crystal density (69–84 mg/header). The EBW test data are given in Table II. The burst amperage (I_b) relative to PETN was as follows:

DDNONA EBW TESTS

Run	Com- ound	Detonation	Burst Amperage			Delay μsec	Wt, mg	%
			Scope A	Scope B ¹	Voltage			
1	PETN	yes	199	194	700	2.5	76.3	49.7
2	PETN	no	185	184	675	2.5	79.2	51.6
3	DDNONA	yes	236	224	775	1.7	70.5	45.4
4	DDNONA	yes	191	194	700	2.5	77.0	49.0
5	DDNONA	no	183	185	675	2.5	77.5	50.5
6	DDNONA	yes ²	193	190	686	2.5	76.6	48.8
7	PETN	no	192	193	686	2.5	74.2	48.3

¹Scope B more accurate than Scope A.

2Low order. Header not broken. All other detonations resulted in fragmentation of header.

45

Impact Sensitivity

The impact sensitivity of DDNONA was determined using a Technopproducts drop-weight tester. Values given are the 50 percent point in cm for a 3-kg and a 2-kg weight.

Spark Sensitivity.	HMX	11-12/3 kg, 29-30/2 kg
	PETN	13-14/3 kg, 45/2 kg
	DDNONA	< 1/3 kg, 2-3/2 kg
PbN ₃		10 millijoules, negative, 3 trials
		15 millijoules, positive, 3 trials
DDNONA		75 millijoules, negative, 3 trials

Thermal Gravimetric Analysis (tga)

The tga of DDNONA was run on the 0.01 to 0.03-mm particle size material in an open platinum cup and under a nitrogen flow of 50 ml/min. The heating rate was approximately 2.5°C/min.

12

Table III

TGA OF DDMONA			
Time, min	Temp, °C	Wt, mg	Total Wt Loss, mg
0	25	8.80	
50	150	8.80	0
55	152	8.80	0
60	175	8.78	0.02
65	191	8.76	0.04
70	205	8.70	0.10
75	209	8.65	0.15
80	232	8.50	0.30
83	240	8.32	0.48
84	243	8.20	0.60
85	245 + 10° exotherm	0.20	8.60
90	250	0.20	8.60
100	288	0.20	8.60
104	300	0.20	8.60

At 243°C and 84 min, the sample gassed off, leaving 0.20 mg of carbon powder. A 10°C exotherm was observed between 84 and 85 min, but returned to baseline.

Differential Thermal Analysis (dta)

The dta of DDNONA was run on a 1.0-mg sample in aluminum under a nitrogen flow of 15 ml/min and at 1-0°C/min. The sample showed a broad endotherm peaking at 230°C followed immediately by a broad exotherm peaking at 260°C. Above 260°C, the sample continuously lost weight.

Melting points reported are uncorrected and were obtained in a capillary using a Mel-temp melting point apparatus. Elemental analyses were determined by Stanford University and by Miss E. McCarthy, SRI Analytical Services. NMR data were obtained by Mrs. L. Stietzel using a Varian HA-100 NMR spectrometer. Values for ^1H Chemical shifts are given in δ units with respect to tetramethylsilane as internal reference, and values for the ^{19}F chemical shifts are given in ϕ units (7) with respect to trichlorofluoromethane as an internal reference. In NMR descriptions, s = singlet, d = doublet, t = triplet, q = quadruplet, m = multiplet. Infrared spectra were run on a Perkin-Elmer Model 137 Infracord spectrophotometer. In IR descriptions, s = strong, m = medium, w = weak, and b = broad.

Thin-layer chromatography was carried out on Eastman Chromagram sheets of silica gel with fluorescent indicator. Anhydrous magnesium sulfate was added to reaction mixtures from fluorinations in acetonitrile to remove residual hydrogen fluoride. Since magnesium sulfate was slightly soluble in acetonitrile, addition of

methylene chloride to the acetonitrile solution reduced this solubility. To remove the small amount of magnesium sulfate that dissolved, from the isolated crude product of the fluorination, the product was dissolved in methylene chloride or ethyl acetate and filtered. Elution of difluoraminonitroaromatic compounds in column chromatography was detected by spraying a spot of the eluate on filter paper with a 0.2 percent solution of *N,N,N',N'*-tetramethyl-p-phenylenediamine dihydrochloride in 50 percent methylene chloride and ethanol (TMPDA reagent); thin-layer chromatograms were also sprayed with TMPDA reagent. TMPDA reagent turned blue in the presence of strong oxidizers such as NF_2 -nitroaromatic compounds. Often the blue color changed to yellow at or above ambient temperature. Densities were determined using a Fisher-Davidson gravitometer.

Caution

The difluoraminonitroaromatic compounds described in this paper are explosives and sensitive to initiation by impact, shock, friction, or other means. Many difluoramino and nitroaromatic compounds are toxic in varying degrees and will cause stains and burns when brought into contact with the skin.

Exploding Bridge Wire Apparatus and Procedure

Exploding bridge wire tests were run with a Reynold's Industries header, type 167-2810, which has a gold wire 30 mils long and 1.5 mils in diameter. The sample was pressed in a brass bushing which was already glued to the header. Dimensions of the pressed sample were 300 mils long and 150 mils in diameter. Samples were weighed to the nearest 0.1 mg and

pressed to a density in the range of 45 to 55 percent of the crystal density of the compound. All samples were ground in 50-mg portions with a mortar and pestle; gloves and a protective shield were used for this operation. The sample particle size (0.01 to 0.03 mm) was determined microscopically with a micrometer having a 2-mm line graduated to 0.01 mm divisions. Criteria used to identify a detonation were the sound of the explosion and the appearance of the brass fragments from the bushing. PETN (military specifications) was used as a standard. The burst amerge was determined at the time of maximum voltage across the wire.

While there has been described in the foregoing what may be considered to be preferred embodiments of the inventions, modifications may be made therein without departing from the teachings of the invention and it is intended to cover all such as fall within the scope of the appended claims.

What we claim is:

20 1. A nitrodifluoraminoterphenyl compound having the formula

wherein R is a radical selected from the group consisting of H and NO_2 .

25 2. The compound 3,3''-Bis(difluoramino)-2,2'',4,4',4'',6,6',6''-octanitro-m-terphenyl.

30 3. The compound 3,3'-Bis(difluoramino)-2,2',2'',4,4',4'',6,6',6''-nonanitro-m-terphenyl.
